UNITED STATES PATENT OFFICE.

FRANCIS SPENCE BAKER, OF TORONTO, CANADA.

RADIATOR.

SPECIFICATION forming part of Letters Patent No. 689,844, dated December 31, 1901.

Application filed February 23, 1901. Serial No. 48,606. (No model.)

To all whom it may concern:

Be it known that I, FRANCIS SPENCE BAKER, architect, a subject of the King of Great Britain, residing at Toronto, in the county of 5 York, Province of Ontario, Canada, have invented certain new and useful Improvements in Radiators, of which the following is a specification.

My invention relates to improvements in 10 all forms of steam or hot-water direct or indirect radiators; and the object of my invention is to preferably provide each section of a radiator with an evaporating-chamber; and it consists, essentially, in forming in each radiator-section, preferably by means of casting, so as to form an integral part thereof, 15 an air communicating evaporating-chamber having no communication with the heating portion or chamber of the steam or hot-water radiator and providing automatic means for regulating the supply of water to said evaporating-chamber of the radiator, as herein-after more particularly explained.

Figure 1 is in part a vertical section through 20 a radiator constructed in accordance with my invention. Fig. 2 is a vertical section through a single section of a radiator constructed in accordance with my invention. Fig. 3 is a diagrammatic view of a radiator constructed 25 in accordance with my invention, showing an automatic means for supplying water to the evaporating-chamber of the same. Fig. 4 is a vertical section through a single section of a radiator constructed in accordance with my invention, showing an alternative form of 30 evaporating-chamber. Fig. 5 is in part a vertical section through a radiator constructed in accordance with my invention, showing only one outlet for the evaporating-chamber.

40 In the drawings like letters of reference indicate corresponding parts in each figure.

A is the radiator, which is made up of any suitable number of sections B, constructed in any of the well-known ways. In the radiator 45 shown C is the supply-cock for the steam or hot water for the radiator, and D the exhaust-cock for same.

a represents the legs of the radiator.

The radiator-sections B communicate with 50 each other by means of the nipples E, of any suitable form.

In carrying out my invention I preferably

cast near or at the top portion of each section B an evaporating-chamber F, which has of necessity no communication with the heating-chambers F² of the said radiator-section. 55

F is the wall or diaphragm which divides the evaporating-chamber F from the heating-chamber F² of the sections B.

Preferably in each evaporating-chamber is 60 formed an aperture G, through which the evaporation (caused by the water in the evaporating-chamber F being sufficiently heated by the heat from the hot water or steam in the heating-chambers F² coming in contact 65 with the wall F' and heating same) escapes into the room. The aperture G will of course be placed in the chamber F so as to be above the level of the water therein. The evaporating-chamber F of each section is connected 70 to the evaporating-chamber of the adjacent radiator-section by means of any of the well-known means, such as nipples E', as will be seen from the drawings. The nipples E' or other connections are preferably flush with 75 the bottom of the evaporating-chambers F, so that the same may be easily cleaned. It will be understood that the evaporating-chambers F, connected together as described, form one large evaporating-chamber G'. It must be 80 understood that, for instance, if I construct one of the sections B with an evaporating-chamber F which is not provided with an aperture G the next evaporating-chamber, or, if desired, any desired one or number of them, 85 will be provided with an aperture G, so that the evaporation may escape therefrom, as will be understood. From this it will be understood that, if desired, the evaporating-chamber G' may be provided with only one aperture G for carrying off the evaporation; but it is preferred to provide the evaporating-chamber F in each section B with an aperture G, so that the distribution of the moisture into the air will be more uniform, as will 90 be understood. The evaporating-chambers G are preferably formed with a semicircular lower portion, as will be seen, so that when they are all connected together they will form a trough H, which will be kept automatically 95 filled with water to, for instance, the height shown by dotted lines.

I is a water-supply pipe leading from any suitable automatically-operated tank J to the

evaporating-chambers G and opening into the same on a level with the bottom of the trough H, as will be understood.

K is the supply-pipe of the tank J.

5 In order to provide for ready cleaning of the trough H, I provide a suitable cap O, preferably screwed onto one end of the evaporating-chamber G', which can readily be removed by disconnecting any suitable coupling P. The 10 coupling P opens from the evaporating-chamber G' on a level with the bottom of the trough H and connects with the exhaust-pipe Q.

R is a stop-cock in the pipe Q. It will be readily understood that when the evaporating-chamber G' is in operation the cock R is closed. In the supply-pipe I is a stop-cock i. When the evaporating-chamber G' is to be cleaned, the stop-cock i is closed and the cock R is opened in order to allow the water 20 in the evaporating-chamber G' to be drawn off before the cap O is removed for further cleaning.

It will of course be understood that the well-known float M in the tank J automatically 25 closes the well-known valve N in the pipe K, so as to prevent the water in the tank J (and consequently in the evaporating-chamber G', as the water therein will always be at the same level as the water in the tank J) from rising 30 beyond a certain level. In case the water in the tank J should rise too high the surplus water will be carried off by the pipe L.

I of course do not confine myself to placing the wall or diaphragm F' in any particular 35 portion of a radiator-loop, nor do I confine myself to any particular shape of the same nor of the evaporating-chamber F. In Fig. 4 will be seen a cross-section of the wall or diaphragm F' shown in alternative form. This 40 diaphragm may be flat, as shown in dotted lines; but it is preferred to make the same with a trough H. I may also provide each radiator-section B with any desired number of evaporating-chambers F, as will be understood.

My improvement in radiators is more particularly applied to cast-iron hot-water or steam direct or indirect heating radiators, although wrought-iron or other classes of radiators can be by ordinary mechanical ability fitted with an evaporating-chamber such as I claim.

From this specification will be understood thoroughly my invention; but I do not confine myself to the construction described, and shown in the drawings, which may be altered in many ways without departing from the spirit of my invention.

What I do claim as my invention, and desire to secure by Letters Patent, is—

1. A radiator comprising a hollow section provided with a partition dividing the said section into two chambers, one of the chambers of said section being provided with an 65 aperture forming an outlet for same, and being further provided with apertures adapted

to receive pipes that control the supply of water thereinto, as described.

2. A radiator comprising a hollow section provided with a partition dividing the said section into a heating-chamber and an evaporating-chamber, the said evaporating-chamber being provided with apertures adapted to receive couplings, another hollow section provided with a partition dividing the said section into a heating-chamber and an evaporating-chamber, the said evaporating-chamber being provided with an aperture forming an outlet for same, and also being provided with apertures adapted to receive couplings, and 75 couplings connecting the evaporating-chamber of both sections together, as described.

3. A radiator comprising a hollow section provided with a partition dividing the said section into a heating-chamber and an evaporating-chamber, the said evaporating-chamber being provided with apertures adapted to receive couplings, and one or more other hollow sections each provided with a partition dividing the said sections into a heating-chamber and an evaporating-chamber, the said evaporating-chamber of any of the said sections being provided with an aperture forming an outlet for same, and also being provided with apertures adapted to receive couplings, 85 and couplings connecting the evaporating-chambers of the adjacent sections together so as to make one common evaporating-chamber for all the sections, as described.

4. A radiator comprising a series of hollow 100 sections, each section being provided near the upper end with a transverse partition dividing it into two chambers, the upper part of each section being provided with an aperture forming an outlet for the upper chamber and the 105 sections being further provided with apertures adapted to receive couplings and to provide communication between like chambers of adjacent sections, and couplings for connecting the sections together.

5. A radiator comprising a series of hollow sections, each section being provided near the upper end with a transverse trough-shaped partition dividing it into two chambers, the said trough-shaped partition of each section being on the same level, the sections being further provided with apertures adapted to receive couplings, and couplings adapted to connect the sections together thus affording communication between like chambers of adjacent sections, and providing a level interior bottom for said partition, all of the sections being provided, at their upper part, with an aperture forming an outlet, as described.

6. A radiator comprising a series of hollow 125 sections, each section being provided near the upper end with a transverse trough-shaped partition dividing it into two chambers, the said trough-shaped partition of each section being on the same level, the sections being further provided with apertures adapted to receive couplings, 130 couplings adapted to con-

nect the sections together thus affording communication between like chambers of adjacent sections, and providing a level interior bottom for said partition, all of the sections being provided, at their upper part, with an aperture forming an outlet, and means for supplying water to the upper chamber of each of said sections, as described.

7. A radiator comprising a series of hollow sections, each section being provided near the upper end with a transverse trough-shaped partition dividing it into two chambers, the said trough-shaped partition of each section being on the same level, the sections being further provided with apertures adapted to receive couplings, couplings adapted to connect the sections together thus affording communication between like chambers of adjacent sections, and providing a level interior

bottom for said trough-shaped partition, all 20 of the sections being provided, at their upper part, with an aperture forming an outlet, the end aperture of one of the end sections of said series of sections being closed, a pipe connected with the end aperture of the other end 25 section of said series of sections and opening into a water-supply tank, and automatic means in said tank for keeping the water in said pipe and said trough-shaped partition at a certain level, as described.

In testimony whereof I have signed my name to this specification in the presence of two subscribing witnesses.

FRANCIS SPENCE BAKER.
